The ornamental design for an electric cooking plate
with middle sensor, as shown and described.

DESCRIPTION

FIG. 1 is a bottom plan view of an electric cooking
plate with middle sensor, showing my new design;
FIG. 2 is a side elevational view thereof;
FIG. 3 is a top plan view thereof;
FIG. 4 is an enlarged fragmentary perspective view
thereof, showing the central part of the top face; and
FIG. 5 is a perspective view of the bottom thereof.
